UNITED STATES PATENT OFFICE.

DANA OSGOOD, OF HOPEDALE, MASSACHUSETTS, ASSIGNOR TO DRAPER CORPORATION, OF HOPEDALE, MASSACHUSETTS, A CORPORATION OF MAINE.

WARP STOP-MOTION FOR LOOMS.

1,366,827.

Specification of Letters Patent. Patented Jan. 25, 1921.

Application filed July 14, 1920. Serial No. 396,141.

To all whom it may concern:

Be it known that I, DANA Osgood, a citizen of the United States, residing at Hopedale, in the county of Worcester and State of Massachusetts, have invented Improvements 5 in Warp Stop-Motions for Looms, of which the following description, in connection with the accompanying drawings, is a specification, like characters on the drawings representing, like characters on the drawings repre-

senting like parts.

This invention relates to warp stop motions for looms, and more particularly to improved means for finding the broken or abnormal warp thread.

15 Looms are now generally supplied with warp stop motions which comprises a series of warp detectors which are supported by the normally conditioned warp threads between the warp beam and shedding mechanism, 20 and associated with the warp detectors is a train of mechanism which, when a detector is allowed to drop to an abnormal position either by a broken or abnormally slack warp thread, effects loom stoppage. It is then 25 the duty of the weaver to find the abnormal warp thread and either tie the ends of the broken thread together, or correct the slackness thereof. There are usually a large number of threads which are spread out into 30 sheet form, and very close together, so that much time is lost in finding the broken or abnormal warp thread and correcting the fault so that the loom may be started and perfect cloth be woven.

35 An important feature of the present invention, therefore, consists of simple and effective means which may be manually operated by the weaver for readily detecting the position of the broken or abnormally 40 slack warp thread. Usually the dropped detector is engaged by a movable member of the train of mechanism when the detector is dropped, and the movable member is brought to rest by the detector, thereby setting 45 the train of mechanism into operation to effect loom stoppage. Before the loom can be started again, the dropped detector must be thrown out of the path of movement of the movable member, and another important feature of the present invention, 50 therefore, consists in a kicker which, under manual control, may be actuated to kick or throw the dropped detector into an indicating position to indicate the location of the

abnormal warp thread and simultaneously therewith, disengage it from the movable member of the train of mechanism.

The above and other features of the invention will best be understood from the following description and accompanying drawings of one good, practical form of the invention, and then the novel features and combinations of parts will be defined by the claims.

In the drawings:

Figure 1 is a sectional side elevation of a loom provided with a warp stop motion of the present invention;

Fig. 2 is an enlarged detail showing the kicker and its connection with one good form of means for impulsively actuating the kicker;

Fig. 3 is a sectional side elevation showing the warp detectors, the kicker, and associated parts; and

Fig. 4 is an enlarged front elevation of the warp stop motion and associated parts, some of the elements being broken away.

The loom frame and the operating parts for effecting the usual weaving operation, 80 may be as usual, and as indicated in Fig. 1, the loom frame 1 has mounted thereon the shedding mechanism which may be indicated as a whole at 2, and rearward of the shedding mechanism are the usual whip rolls 3, 85 over which the warp threads pass from the warp beam to the shedding mechanism. The lay 4, its actuating means 5 and the crank shaft 6 may be of usual construction.

Supported upon the loom frame between 90 the shedding mechanism and whip rolls is the warp stop motion which comprises a series of warp detectors which are supported in normal raised position by intact and normal warp threads. When a warp 95 thread breaks, however, the supported warp detector is permitted to drop and is then brought into a position to arrest a movable member of a train of mechanism and effect loom stoppage.

In the present instance of the invention, the loom frame has connected at each side thereof a support 7, one of which is indicated in Fig. 4. The support 7 is sustained from the loom frame by any appropriate 105 means, as for instance, the bracket 8 which may be secured to the support 7 at the upper portion thereof, but which may be otherwise

associated with the support to hold it in proper position between the shedding mechanism and the whip rolls. Extending between the supports 7 are the rods 9 over which pass, in the present instance, the warp threads *a*. Extending between the supports 7, one at each side of the loom, are the detector guides 10 which pass through elongated slots 11 formed in the warp detectors, and consequently guide the detectors in their rising and falling movements.

The warp detectors and the means for arresting the operation of the loom when a detector drops, may be variously constructed and formed, but in the present instance of the invention, and as showing one good, practical form of warp detectors and stopping mechanism, the warp detectors are each formed of thin metal, and in addition to the guiding slots 11 in the upper portion thereof, each detector has a lower slotted portion 12 and preferably a closed lower end 13. In the slotted portions 12 of the detectors are the toothed detector slides, one of which in each of the slots, is fixed, and the other of which is given a reciprocating movement. In the present instance the fixed member of the slides consists of a transversely-extending bar 14 which may be secured to the supports 7 as indicated at 15, Fig. 4. Each of the fixed bars or slides 14 is provided with a series of teeth 16.

The bars or slides 14 are each provided with a central guide-way in which is mounted for reciprocation the toothed bar or slide 17, the teeth of which may extend somewhat above the teeth of the fixed bars 14. The reciprocating toothed slides 17 are given their reciprocating movement by an arm 18 having a slot and pin connection 19 with the bars 17, and the arm 18 is actuated from another arm 20 connected to a rod or link 21, the construction being such that should the reciprocating toothed bar 17 or either of them, be arrested in its reciprocation, it will effect loom stoppage. The means for stopping the loom through the arresting of one of the toothed bars 17 is well known in the art, and since it forms no special part of the present invention, it is not deemed necessary at this time to illustrate and describe the same in detail.

All of the parts thus far described may be of usual construction and may operate in the usual manner to stop the loom when one of the warp detectors is permitted to drop by the associated warp thread, either by breakage thereof or by its becoming too slack for perfect weaving purposes.

The two supports 7, one at each side of the loom, as hereinbefore described, are extended downwardly below the lower ends of the warp detectors as indicated in Figs. 1, 3 and 4, and are each provided with a guide-way 22, Figs. 3 and 4, in which is guided

for vertical movement, the kicker 23. The kicker 23 extends between the two supports 7 below the lower ends of the warp detectors, and is limited in its reciprocating movement upwardly by a stop 24 which may be conveniently formed as the upper limiting wall of the guide-ways 22. Pivotally connected to the kicker 23 at 25 is the yoke 26, the converging end portions of which are united by a bolt 27 and connected by a link 28 with the arm 29 of a manually-operating means which, in the present instance of the invention, consists of a treadle pivotally mounted at 30 and having a foot-piece 31 conveniently positioned for actuation by the weaver.

When the warp threads are normal, that is, when they are intact and duly under tension, the warp detectors will be held in their raised or normal position, as indicated in Figs. 1 and 3; but should a warp thread break or become unduly slack or abnormal, the suspended warp detector will drop (as indicated by dotted lines in Fig. 3) until the upper wall 31 of the slot 12 thereof will engage between the teeth of the relatively fixed and movable warp detector slides 14 and 17, whereupon the movable slide will be arrested and effect loom stoppage, as usual in this class of warp stop motions, and the dropped detectors will remain pinched between the teeth of the relatively fixed and movable slide bars. It is then the duty of the weaver to locate the abnormal warp thread which has caused loom stoppage. In the present invention, the weaver thereupon manually actuates the kicker, which has the effect of impulsively throwing upward the dropped detector from its lowered position, as indicated in Fig. 3, and causing it to slide above the line of normally-suspended warp-detectors. Owing to the limiting stop 24 which limits the kicking movement of the kicker, the normally positioned warp detectors remain undisturbed. The upward movement of the kicker also detaches the dropped detector from between the teeth of the toothed slide bars and unlocks them so that when the end of the broken warp is pieced or the undue slackness is taken up, the loom is ready to start into operation.

In the present embodiment of the invention, the warp detectors are shown as of a particular type which is found to be well suited for the purposes of the present invention; but it is to be understood that the invention is not limited in this respect, because the warp detectors may be variously formed, the essentials being that when a warp detector shall have been dropped to its lowered position by a warp thread, the kicker may be manually operated to throw the detector upwardly or into an indicating position to enable the weaver to readily locate and piece or take up the slack of the abnor-

mal warp thread, and simultaneously therewith, to unlock the dropped detector from its stopping position.

What is claimed is:—

5. 1. In a warp stop motion for looms, the combination of a series of warp detectors adapted to be supported by warp threads, means for stopping the loom when a warp thread breaks or becomes too slack, a kicker, 55 and manually operated means for causing the kicker to kick a dropped detector upwardly beyond the normal position of the detectors and locate the abnormal warp thread.
10. 2. In a warp stop motion for looms, the combination of a series of warp detectors adapted to be supported by normal warp threads, means for stopping the loom when an abnormal condition occurs in a warp 60 thread and a detector is permitted to drop, a kicker positioned below the series of warp detectors, and means for manually operating the kicker to impulsively lift or throw the drop detector above the normal position 65 of the warp detectors and locate the abnormal warp thread.
15. 3. In a warp stop motion for looms, the combination of a series of warp detectors, a kicker, and manual means for operating the 70 kicker to throw a dropped detector upwardly in the vertical plane in which it is normally suspended.
20. 4. In a warp stop motion for looms, the combination of a series of warp detectors, 75 toothed detector slides adapted to be engaged by a dropped detector to stop the loom, and a manually operated kicker for disengaging the dropped detector from the toothed slides and locating the abnormal 80 warp thread.
25. 5. In a warp stop motion for looms, the combination of a series of warp detectors, relatively movable toothed detector slides adapted to be engaged and locked from 85 relative movement by a dropped detector to stop the loom, a kicker, and manually controlled means for operating the kicker to 90 unlock the toothed slides and by upward movement of the dropped detector to locate the abnormal warp threads.
30. 6. In a warp stop motion for looms, the

combination of a series of warp detectors, relatively movable toothed slides adapted to be locked from relative movement by a dropped detector to stop the loom, a kicker 55 extending transversely of the loom below the warp detectors, and manually operated means for impulsively actuating the kicker to unlock the toothed slides from a dropped detector and indicate the position of the ab- 60 normal warp thread.

7. In a warp stop motion for looms, the combination of a series of warp detectors, relatively movable toothed slides adapted to be locked from relative movement by a 65 dropped detector to stop the loom, a kicker, and manually controlled means for operating the kicker to throw the dropped detector into an indicating position and to unlock the toothed slides, and a stop for limiting the 70 movement of the kicker to prevent disturbance of the undropped detectors.

8. In a warp stop motion for looms, the combination of a plurality of rows of warp detectors adapted to be supported by normal 75 warp threads, a kicker extending transversely of the loom and arranged to kick a dropped detector in any of the rows to throw the dropped detector upwardly and thereby locate the abnormal warp thread, 80 and means for operating the kicker.

9. In a warp stop motion for looms, the combination of two rows of warp detectors adapted to be supported by normal warp threads, a kicker extending transversely of 85 the loom and arranged to impulsively throw a dropped detector in either row upwardly to indicate the position of the abnormal warp thread, and means for operating the kicker.

10. In a warp stop motion for looms, the combination of a series of warp detectors adapted to be supported by normal warp threads, a kicker extending transversely of the loom and arranged to kick a dropped detector upwardly to indicate the position of the abnormal warp threads, and a foot treadle for operating the kicker.

In testimony whereof, I have signed my name to this specification.

DANA OSGOOD.
